FOOD PACKAGING TRAY

Roy W. Bloch, Northbrook, Ill., assignor to Ekco Products, Inc., Wheeling, Ill.

Filed Sept. 14, 1970, Ser. No. 24,985

Term of patent 14 years

Int. Cl. D9—03

U.S. Cl. D9—185

FIG. 1

FIG. 2

FIG. 3

FIG. 4

FIG. 5

FIG. 6

FIG. 1 is a top plan view of a food packaging tray showing my new design,

FIG. 2 is a side elevational view thereof, taken from the back of FIG. 1,

FIG. 3 is an end elevational view thereof taken from the left of FIG. 1,

FIG. 4 is a vertical section taken along line 4—4 of FIG. 1,

FIG. 5 is a side elevational view thereof taken from the front of FIG. 1,

FIG. 6 is an end elevational view thereof taken from the right of FIG. 1.

I claim:

The ornamental design for a food packaging tray, as shown.
